UNITED STATES PATENT OFFICE

DAVID L. MOORE, OF BARTLESVILLE, OKLAHOMA, ASSIGNOR TO PHILLIPS PETROLEUM COMPANY, OF BARTLESVILLE, OKLAHOMA.

COMBINED SNUFFER AND GAS TRAP

Application filed September 16, 1926, Serial No. 135,898. Renewed October 26, 1929.

This invention relates to improvements in oil or gas well equipment, and more especially to a combined snuffer and gas trap, which not only serves to extinguish or snuff out oil or gas well fires, but also serves, when desired, to trap and remove all poisonous and undesirable gases from the well casing.

One advantage of the device is that it will extinguish gas fire of large volume, particularly beneath the derrick floor. Secondly, it will in no way interfere with the men at work on the derrick floor. Then too, by extinguishing the fire, loss of rig and tools is entirely obviated.

An equally important advantage is in the gas trap, forming the distinguishable and salient part of the invention, which will carry off the large volumes of gases, preventing the same from reaching the derrick floor, and causing injury to the workmen thereon. Not only this, it will greatly reduce fire hazards, and it may be used at all times while drilling in gas formations.

Briefly, the invention has reference to a structure which comprises primarily two parts; first, the snuffer or fire extinguisher; and secondly, the gas trap, these two parts being connected together into a single unit, and being constructed so as to permit them to be incorporated in the well casing without requirement of alterations of the latter.

Other features and advantages and the specific details of construction will become apparent from the following description and drawings.

In the drawings:—

Figure 1 is a side elevation with portions broken away and shown in section, disclosing the entire device and the association of the parts.

Fig. 2 is a horizontal section taken approximately upon the plane of the line 2—2 of Fig. 1, looking in the direction of the arrow.

In the drawing, the reference character 1 designates generally the so-called snuffer. This comprises a central pipe 2 surrounded by a casing 3. One end of the pipe projects below the casing as at 4 and is screw threaded for connection to the adjacent section of the well casing (not shown). The intermediate

enclosed portion of the pipe is provided with semi-circular slots 5 arranged at vertically spaced points in staggered relation in order to produce a counter-current in the gases as they come up from the well casing.

The reference characters 6 designate simple connections for steam conducting pipes. The steam is of course generated in a boiler (not shown). The trap is generally designated by the reference character 7 and this comprises a casing 8 of the configuration shown, the same being connected at its bottom to the extended upper end of the aforesaid pipe 2. The interior of this casing constitutes an expansion chamber for the gases. At the top of the casing, is a screw threaded connection 9 to connect to an adjacent connection of the well casing. On one side, adjacent the center of the casing is a relatively small steam supply pipe 10, while at a diametrically opposite side is the gas discharge 11 which is of a considerably large diameter in comparison to the pipe 10.

Attention is also called to a small L-shaped tube 12 which extends into the discharge 11. As before indicated, the pipes 6 serve to supply steam from the boiler and modifying the arising gases coming up from the well casing. This steam passes into the chamber formed between the casing 3 and the pipe 2, and then passes through the diametrically disposed and staggered slots in the pipe, where, as before stated, a counter-current in the gases is produced. The trap being built on top of the snuffer, provides an expansion chamber, causing the gases to lose velocity.

The tube 12 projecting into the discharge, supplies a steam jet which creates a vacuum and which in conjunction with the pressure produced through the steam pipe 10, serves to eject gases in a forceful manner through the discharge 11.

It is believed that by considering the description in connection with the drawings, persons familiar with devices of this class will be able to obtain a clear understanding of the same. Consequently, a more lengthy description is believed unnecessary.

invention claimed, may be resorted to if desired.

Having thus described my invention, what I claim as new is:—

- 5 1. In a combination snuffer and gas trap of the class described, a gas trap comprising a casing, a relatively small steam supply pipe connected with one side of the casing, a relatively large gas discharge pipe connected to a substantially diametrically opposite side 10 of the casing, and a substantially L-shaped steam conducting tube located in said discharge pipe and having its discharge branch disposed outwardly, and means carried by said casing whereby it may be connected with a well casing.
- 20 2. A combined snuffer and gas trap having an opening in its top, and provided with an outlet, and fluid-pressure means for directing to the outlet and away from the opening, gas which rises in the combined snuffer and gas trap.
- 25 3. A combined snuffer and gas trap having an outlet, a tubular member in the top of the combined snuffer and gas trap and provided intermediate its ends with a nozzle discharging into the outlet, and means for admitting fluid-pressure into the tubular member.
- 30 4. In a device of the character described, tubular means adapted to be interposed in a well casing, means cooperating with the tubular means for breaking up the continuity of the upward flow of the well fluid, a lateral branch for the tubular means arranged above the breaking means, and means for inducing the well fluid to flow through said lateral branch.
- 35 5. In a device of the character described, tubular means adapted to be inserted in a well casing, provided with slots to admit steam into the tubular means for breaking up the continuity of the upward flow of well fluid, said tubular means including an expansion chamber arranged above said slots, a lateral branch extending from the expansion chamber, and means for inducing the flow of well fluid from the expansion chamber through said lateral branch.
- 40 6. A device of the character described, comprising tubular means adapted to be interposed in a well casing, means for introducing steam into the tubular means in such manner as to break up the continuity of the upward flow of well fluid through the casing, a lateral branch leading from the tubular means, and means having an outlet in said lateral branch for introducing a pressure fluid into the branch to divert the upward flow of the well fluid through said lateral branch.
- 45 7. In a device of the character described, a tubular member having threaded ends to allow said member to be interposed in a well casing, said tubular member having upper and lower oppositely disposed slots, means for feeding steam through said slots, a por-

tion of the tubular member above the slots being enlarged and forming an expansion chamber, a lateral branch leading from the expansion chamber, and means having an outlet within the lateral branch for directing a pressure fluid into said branch to cause well fluid from the expansion chamber to flow through said branch.

8. In a device of the character described, a tubular member having threaded ends to allow said member to be interposed in a well casing, said tubular member having upper and lower oppositely disposed slots, means for feeding steam through said slots, a portion of the tubular member above the slots being enlarged and forming an expansion chamber, a lateral branch leading from the expansion chamber, means having an outlet within the lateral branch for directing a pressure fluid into said branch to cause well fluid from the expansion chamber to flow through said branch, and a steam introducing pipe connected to the expansion chamber portion of the tubular member and arranged substantially coaxial with the axis of said branch.

In testimony whereof I affix my signature.
DAVID L. MOORE.
